ELECTRIC SWITCH.

1,330,137.

Specification of Letters Patent. Patented Feb. 10, 1920.

Application filed June 14, 1918. Serial No. 304,105.

To all whom it may concern:

Be it known that I, CLARENCE D. PLATT, a citizen of the United States of America, residing at Bridgeport, Connecticut, have invented a new and useful Electric Switch, of which the following is a specification.

My invention relates to switches of the enclosed type.

Special objects of the invention are to provide efficient and at the same time simple and inexpensive mechanism for securing the switch cover closed and the switch mechanism in a predetermined condition, such as for instance in the open-circuit position.

Certain switches of this type are usually provided with an upstanding lug projecting through the cover and adapted to receive a padlock or other fastening device. This upstanding and projecting lug is a source of frequent trouble in the packing and shipping of the switch, being quite often broken or bent in the shipment of the switch and further necessitating the use of a shipping box of sufficient size not only to take the switch box, but this projecting lug as well. An important object of this invention is to overcome and avoid these various objections and disadvantages.

In the form of the invention herein disclosed the combined lock for the switch cover and switch mechanism is provided by means of outstanding registering loops on the cover flange and the operating handle, respectively, adapted to receive a padlock or other securing device and the securing device for the cover is provided in the form of an upstanding bar or lug which when in use projects above the cover but which when not in use can be dropped down into the box in a non-projecting position.

The various other features of the invention and details of construction will all appear as the specification proceeds.

In the accompanying drawing I have illustrated the invention embodied in one of its practical commercial forms but I would have it understood that modifications and changes may be made in the structure without departure from the spirit and scope of the invention as defined in the appended claims.

In said drawing:

Figure 1, is a plan view of my switch,

showing the cover partly broken away for the purpose of exposing the switch mechanism.

Fig. 2, is a side elevation of the same with the end portion of the switch box broken away and shown in section.

Fig. 3, is a view of the lower end of the box illustrating in dotted lines how the securing bar may be dropped down into inoperative non-projecting position.

Fig. 4, is an enlarged sectional view taken substantially on the plane of the line 4-4 of Fig. 2.

Fig. 5, is a broken detail view illustrating a method of forming the locking lug for the handle.

The switch box, which is designated 5, may be of any usual or suitable construction and is shown provided with a movable cover 6 hinged at the upper end of the box body at 7.

The switch mechanism illustrated consists of a switch base 8 secured in the bottom of the box and supporting a pair of switch blades 9 connected by a bar 10 and pivoted at 11, said switch blades being adapted to make engagement with the relatively stationary switch contacts 12.

The switch mechanism is operated in the present disclosure by an oscillating arm 13 connected at 14 with an arm 15 extending from the cross bar 10. This oscillating switch operating arm has an angularly bent base portion 16 secured in flat engagement with a locking disk 27 fastened to the inner face of a bearing disk 17 which is rotatably seated in a bearing opening 18 formed in the wall of the switch box. (See Fig. 4.)

External operating means are provided for the switch in the form of a handle 19 secured at the outer face of the bearing disk 17.

For the purpose of providing the lock between the cover and switch, the cover is shown provided with a laterally outstanding securing loop 20 and the handle is shown provided with a corresponding loop 28 registering with the cover loop, these loops being designed to receive the hasp 22 of a padlock, or a sealing wire or other suitable securing device.

The cover loop is formed in the present disclosure by providing the cover with an

angularly extending dependent flange 23 and by severing a strip at the edge of said flange along the line 24 and then deflecting said partially severed strip outwardly as indicated in Figs. 2 and 3 into the form of the loop 20. A co-extensive opening 25 is also shown formed in the flange above this loop strap so as to facilitate the passage of the hasp of the padlock through the loop.

10 The handle-carried loop is provided in the case illustrated, by means of plate member 26 secured at the outer face of the bearing disk, inside the handle proper and which is formed with a bent-over and angularly outstanding lug 21 at its upper end provided with a perforation 28 registering with the perforation in the cover loop. This perforation 28 in the handle-carried loop is provided in the illustration 20 by forming a slot in the end portion of the plate and then bending out the lug 21 on a transverse line 29 intersecting the intermediate portion of said slot, (see Fig. 5). This, as shown in Figs. 2 and 3, provides 25 co-extensive perforations in the lug and adjacent portion of the plate 26 facilitating the entry of the padlock hasp and permitting the padlock to lie close against the side of the box. The handle-carried member 26 30 at the outer wall of the box and the locking disk 27 at the inner wall of the box hold the bearing disk seated in the bearing opening, as clearly shown in Fig. 4, and said parts may be secured in assembled relation, 35 as indicated, by means of rivets 30 passed through from the handle at the outside of the box to the operating connection 16 at the inside of the box.

The mechanism disclosed is intended to 40 secure the cover closed and the switch in the open-circuit position. Consequently, the parts are so designed that when the handle is thrown to the "off-circuit" position, the loop carried thereby will register 45 with the loop upon the cover. In this relation of the parts the padlock hasp, or other securing device, may be passed through the aligned loops and the switch will be thereby secured in open-circuit position and the box 50 cover closed. In this condition of the parts the box cannot be opened and the switch cannot be closed, except of course by one authorized, who would be provided with a key for opening the padlock.

55 Means are also provided in the switch construction herein disclosed for securing the box closed while leaving the switch free to be operated, said means consisting of a locking plate or post 31 projecting through 60 a slot 32 in the cover and provided with a perforation 33 in such projecting portion for receiving the hasp 34 of a padlock or other securing device. To prevent this locking lug or bar from standing in the way

when the box is being packed for shipment, 65 or storage, I have shown said bar as pivotally secured to the lower wall of the box by means of a screw 35 which passes freely through a perforation 36 provided in said wall and engages at the inner side of said 70 box in a screw seat formed in the bar. By loosening this screw it will be evident that when the cover is open this locking bar may be turned down inside the box as indicated in dotted lines in Fig. 3 so as not to project 75 beyond the edge of the box. The inner end of the screw is preferably headed over as indicated at 37 so that said screw cannot be detached or become lost. To position and hold the locking bar in its upright relation I have shown the box wall as provided with spaced inwardly directed indentations 38 forming spaced shoulders to engage the opposite edges or shoulders on the bar. The shank of the screw is made of sufficient 80 length between the inner surface of the securing bar and the head 37 to permit the screw being unloosened far enough for the bar in its turning movement to clear the holding shoulders 38, provided on the box 85 wall, as will be clear from Fig. 2. The securing bar is usually made of spring metal and provided with shoulders 39 to engage over the top of the box. This enables the bar to be used as a latch for fastening the 90 cover when the padlock 34 is not in use.

In practice, when the switch parts are assembled, the locking bar 31 is usually turned down into the box into the dotted position indicated at 31 so that said bar does not 100 project and the switch can then be packed in a suitable shipping box of but slightly greater size than the switch box. When the switch is to be used, the cover is opened and the locking bar is turned up into its projecting position, whereupon the screw 35 may be tightened and the bar will then be securely held in its upstanding operative relation. When the locking bar is in use 105 and the padlock 34 has been applied to the outer extended end thereof, said bar cannot be released by manipulation of the screw 35 by reason of the fact that said screw cannot be withdrawn, hence the parts are securely held even though an attempt is made 110 to gain admission to the box by manipulation of the screw 35.

I claim—

1. In an electric switch, the combination of a box having a movable cover provided with an angular dependent flange, said flange carrying a loop outstanding from the side of the box, switch mechanism in the box, an operating handle for said switch mechanism journaled in the wall of the box and 120 provided with an outstanding loop registering in one position of the switch mechanism with the outstanding loop on the flange of

the cover, to receive a securing device engageable with the registering loops for securing the cover closed with the switch mechanism in a predetermined condition.

5. 2. In an electric switch, a switch box provided with a movable cover having an angular dependent flange, said flange having an opening therein and having the edge portion of the flange below said opening formed outwardly into a loop, switch mechanism in the box and an operating handle for said switch mechanism journaled in the box and provided with an outstanding loop registering with said flange loop in a predetermined position of the switch handle.

3. In an electric switch, the combination of a box provided with a movable cover having a dependent angular flange, said flange having a strip at the edge thereof severed 20 from the body of the flange and formed outwardly into a loop, switch mechanism in the box and an operating handle for said switch mechanism journaled in the box and provided with an outstanding securing loop, 25 registering with said flange loop in a predetermined position of the operating handle.

4. In an electric switch, the combination of a switch box provided with a movable cover, said cover having an outstanding securing loop at one side of the box, switch mechanism in the box, an operating handle for said switch mechanism journaled in said wall of the box, and a plate carried by said handle at the outer surface of the box wall 35 and substantially parallel thereto, said plate having an angularly projecting loop registering with the loop on the cover in a predetermined position of the handle.

5. In an electric switch, the combination 40 of a switch box having a movable cover provided with an outstanding securing loop, switch mechanism in said box, an operating handle for said switch mechanism journaled in the wall of the box and provided with a plate at the outer face of said wall, said plate having a slot therein and being bent angularly at a point intermediate the ends of said slot to provide an angularly outstanding lug having a perforation therein 45 extensive with a perforation in the adjacent portion of the plate and said perforated lug registering with the securing loop on the cover in a predetermined position of the handle.

55. 6. In an electric switch, the combination of a switch box provided with a movable cover having a securing loop, said switch box having a bearing opening in one wall thereof, a bearing disk journaled in said opening, switch mechanism in the box, a switch operating connection secured to said bearing disk inside the box, and a handle member secured to the bearing disk at the outer surface of the switch box, said handle mem-

ber having a portion overlying the adjacent side wall of the switch box and terminating in an angularly outstanding perforated lug registering with the cover loop in a predetermined position of the handle.

7. In an electric switch, a switch box provided with a movable cover, an upstanding cover securing member pivotally secured on the wall of the switch box so that it may be swung up into position to secure the cover or be folded down into non-projecting position within the box, and means for securing said cover securing member in the upstanding operative position.

8. In combination, a switch box provided with a movable cover having a slot therein, 80 a securing bar supported on one wall of the switch box and arranged to project up through said slot in the cover, and means for fastening said securing bar in upstanding operative position or in non-projecting 85 position within the switch box.

9. In combination, a switch box provided with a movable cover, a cover securing bar pivotally supported on one wall of the box and adapted to be swung on its pivotal support from a non-projecting position within the box up into a projecting position for co-operation with the cover, and co-operating shoulders on the securing bar and box wall 90 for holding the securing bar in its operative 95 projecting position.

10. In combination, a switch box provided with a movable cover, a securing bar, a screw member pivotally supporting said securing bar on one wall of the box and adapted when 100 loosened to permit the securing bar to be swung from an upstanding operative position down into a non-projecting position within the box, said screw member being headed over at its inner end to prevent entire detachment of the same, co-operating shoulders on the securing bar and box wall 105 for holding the securing bar in its upstanding position, and said securing screw being of sufficient length to enable the screw being 110 loosened far enough for the securing bar to clear said shoulders in the movement of the bar from projecting to non-projecting position.

11. In combination, a switch box provided 115 with a movable cover, said box having spaced positioning shoulders on the inner wall thereof, a cover securing bar adapted to be positioned between said shoulders, and a pivotal support for said securing bar 120 adapted to enable the securing bar being swung from an upstanding position between the positioning shoulders down into a non-projecting position within the box.

12. In combination, a switch box comprising a body member and a cover member, a securing bar carried by one of said members and arranged in a projecting position to co-

4
operate with the other member, and means for supporting said securing bar so that the same may be shifted from a non-projecting inoperative position to a projecting operative position.

13. In combination, a switch box provided with a movable cover, a securing bar mounted in the switch box and adapted to project up beyond the cover, said bar having a per-

foration in the projecting portion thereof to 10 receive a padlock or the like, and means for supporting said securing bar within the box so that the same may be lowered into an inoperative non-projecting position within the box or be shifted into an upstanding 15 operative position with the perforation therein standing above the cover.

CLARENCE D. PLATT.
